(57) **CLAIM**

The ornamental design for a travel potty as shown and described.

DESCRIPTION

FIG. 1 is a perspective view of a travel potty according to a first embodiment;

FIG. 2 shows a left side view thereof;

FIG. 3 shows a right side view thereof;

FIG. 4 shows a back view thereof;

FIG. 5 shows a front view thereof;

FIG. 6 shows a top view thereof;

FIG. 7 shows a bottom view thereof;

FIG. 8 is a perspective view of a travel potty according to a second embodiment;

FIG. 9 shows a left side view thereof;

FIG. 10 shows a right side view thereof;

FIG. 11 shows a back view thereof;

FIG. 12 shows a front view thereof;

FIG. 13 shows a top view thereof; and,

FIG. 14 shows a bottom view thereof.

The broken lines represent portions of the travel potty that form no part of the claimed design.
